US00D879258S

(12) **United States Design Patent** (10) **Patent No.:** **US D879,258 S**
(45) **Date of Patent:** **** Mar. 24, 2020**

(54) **QUICK CONNECTION COUPLER**

(71) Applicant: **NELSON IRRIGATION CORPORATION**, Walla Walla, WA (US)

(72) Inventors: **Mathew L. Zimmerman**, Walla Walla, WA (US); **Craig B. Nelson**, Walla Walla, WA (US); **Chad D. Leinweber**, Walla Walla, WA (US); **Joseph Daniel Sinden**, Walla Walla, WA (US)

(73) Assignee: **NELSON IRRIGATION CORPORATION**, Walla Walla, WA (US)

(**) Term: **15 Years**

(21) Appl. No.: **29/643,876**

(22) Filed: **Apr. 12, 2018**

(51) **LOC (12) Cl. 23-01**

(52) **U.S. Cl.**

USPC **D23/262**

(58) **Field of Classification Search**

USPC D23/259-265; D8/72, 382-383, D8/394-396; 285/80, 82, 205, 308, 304, 285/312, 321-322, 325-326

See application file for complete search history.

(57) **CLAIM**

The ornamental design for a quick connection coupler, as shown and described.

DESCRIPTION

FIG. 1 is a bottom perspective view of the quick connection coupler of the invention;

FIG. 2 is a bottom view thereof;

FIG. 3 is a top plan view thereof;

FIG. 4 is a front view thereof;

FIG. 5 is a rear view thereof;

FIG. 6 is a left side view thereof;

FIG. 7 is a right side view thereof; and,

FIG. 8 is a top perspective view thereof.

The dashed broken lines depict portions of the quick connection coupler that form no part of the claim.

1 Claim, 8 Drawing Sheets
